UNITED STATES PATENT OFFICE.

HARVEY C. MASLAND, OF PHILADELPHIA, PENNSYLVANIA.

SPLINT FOR THE SETTING AND RETAINING IN PLACE OF FRACTURES OF THE LONG BONES OF THE LIMBS.

Application filed March 3, 1921. Serial No. 449,409.

To all whom it may concern:

Be it known that I, HARVEY C. MASLAND, a citizen of the United States, residing in the city and county of Philadelphia, State 5 of Pennsylvania, have invented a new and useful Splint for the Setting and Retaining in Place of Fractures of the Long Bones of the Limbs, of which the following is a specification.

10 My invention relates in general to the class of extensible splints which are more particularly applicable for the setting of the femur or the humerus, although my splint may be used to advantage in connection with fractures of the bones of the forearm or of the 15 lower leg.

The object of my invention, broadly considered, is the construction of a compound splint made of readily moldable, bendable 20 or pliable elements adapted to assume the shape of particular parts of the human body, and to be molded or bent to fit such parts and to be attached thereto,—in combination with relatively adjustable compound extension devices attached to the moldable elements in such manner that they can be moved upon each other to effect the separation of the moldable members after the latter have been attached to the body.

25 In the fracture of the long bones where a want of apposition at the point of fracture has to be overcome by traction, it is of importance that the traction element should be such as effectively to occasion the desired apposition with as little inconvenience and pain to the patient, with as little injury to the tissues and with as perfect a replacement of the fractured bone, as is possible.

30 My invention, generally speaking, comprehends a non-irritating splint such as will assure the necessary degree of reduction under continuing traction.

35 My invention further comprehends a splint of the character typically illustrated in the accompanying drawings and herein-after described, which possesses the advantages of being readily moldable to the varying curves of the body in the region of the broken part, the moldable elements being 40 adapted to be connected with the separable members, with the result that there is a more rigid and perfect attachment of the splint as a whole to the body, assured prevention of lateral or longitudinal slip, and more perfect

distribution of strain and pressure, than can 55 be secured with splint devices now commonly used.

My invention still further comprehends reliable means for securing the splint members in casts of plaster of Paris or other 60 binding material, at any desired point or points, for anchoring them to the body.

In connection with the separable members of my splint, I employ one or more bridges adjustable to and spanning the cross diameters of the fractured parts, either above or below the fracture, which are attached to the sides of the splint members at any desired point so as to add rigidity and support to the splint as a whole.

To make the bridge more effective, I apply to its spanning portion, devices to so adjust it as to permit it to act as a rigid support for the exercise of traction in any desired direction vertical to the axis of the 75 bone, in order to bring up the laterally displaced end of the broken bone to proper normal alignment or apposition with the other end.

To effect the separation of the movable 80 members, I employ and connect with them turnbuckle devices to exercise and effect the required longitudinal tension or strain necessary to secure the desired alignment of the separated and overlapped ends of the 85 bone.

From the foregoing explanation, it will be understood that the moldable and attachable elements of my splint are so combined with the separable or traction elements and means 90 for effecting the separation that by obvious and easy adjustments, traction upon both parts of the broken bone can be exerted in the desired direction.

To protect the body of the patient from 95 the effect of the otherwise angular and irritating surface of the moldable members which are adapted when bent into the proper forms to press against the body of the patient to retain the splint as a whole in the 100 desired position,—I wrap these elements either before or after application, with cotton or other preferred soft material in the nature of a padding, which I conveniently retain in place with a covering of leather, either real or artificial, or other water-proof material, cut to the desired lengths with relation to the members to which it is applied.

and having eyelets along the opposite meeting edges through which laces can be passed to hold the padding in place.

For the purpose of illustrating my invention, I have shown in the accompanying drawings forms thereof which are at present preferred by me, since they will give in practice satisfactory and reliable results, although it is to be understood that the various instrumentalities of which my invention consists can be variously arranged and organized and that my invention is not limited to the precise arrangement and organization of these instrumentalities as herein shown and described.

In the drawings:—

Figure 1 represents a side elevation of a patient assumed to have a fractured right femur, with my splint illustrated as applied.

Figure 2 represents a top plan view of the patient and splint represented in Figure 1.

Figure 3 represents a top plan of my splint before application.

Figure 4 represents a side elevational detail of the tail of the body member of the splint.

Figure 5 represents a side elevational detail of a part of one of the side members of the leg member of the splint.

Figure 6 represents a sectional plan illustrative of a construction of pelvic ring.

Figure 7 represents a horizontal section, partly in plan, of one of the turnbuckles which I use to effect the separation of members of the leg element of my splint.

Figure 8 represents a detail, sectional on the line 8—8 of Figure 7.

Figure 9 represents an elevation of the bridge which I use in connection with the separable members of the leg elements of my splint.

Figure 10 represents a fragmentary section of the lower part of the separable member of the leg portion of my splint.

Figure 11 represents a fragmentary perspective of a part of the bridge and of the lifting band which is supported by and movable with the bridge.

Figures 12 and 13 represent, respectively, a front elevation and a rear elevation of a patient assumed to have a fractured right humerus, with my splint applied.

Figure 14 represents a perspective detail of my splint removed from the foregoing patient.

Similar numerals of reference indicate corresponding parts.

Referring first to the first eleven figures of the drawing which illustrates the application of my splint to a fractured femur, the body of the patient is designated 1,—the thigh the femur of which is assumed to be broken 2,—the foot of the leg 3,—and the calf shown as wrapped in a plaster cast, 4.

The upper, moldable, fixed element which is adapted, in the application of my splint, to

be shaped to the side of the patient's body and attached thereto by bands 5,—is designated 6, and hereinafter at times referred to as the body splint.

7 designates the lower, moldable, fixed element which is connected with the upper fixed element 6 by a turnbuckle device hereinafter described. This element is bent back upon itself to form a double or loop-like, extended member, in connection with which a "Buck" extension may be used. This extension, being well known to surgeons, it is unnecessary to describe. The lower element 7, at times, hereinafter refer to as the leg splint.

Both of the elements 6 and 7 are preferably made of bendable or pliable metal which can be bent to assume and follow the outline of the patient's body or leg. I do not, however, confine myself to metal as other bendable substances may be used instead.

8 designates an adjustable pelvic ring for my splint, which is adapted to rest on the ischium, pubic bone and ilium, and which serves the purpose of distributing the pressure and strain resulting from its application.

To this pelvic ring are connected by any preferred means an extension 9 of the inner bend of the moldable element 7, the outer bend of which is slidably connected with the body element 6.

Both bends of the lower fixed element 7 are, as explained, made of strips of metal or other bendable material, the outer bend being connected by a turnbuckle attachment 100 of the body splint 6, and the inner bend being connected by another turnbuckle device to the extension 9.

Collars 39 encompass the overlapping connecting lengths of the bends with the body 105 splint and the extension.

The turnbuckle devices which connect the leg splint 7 with the body splint 6 and the extension 9, may be of any preferred construction. I prefer to make them in the form of such rotary thumb-turning devices as are best illustrated in Figures 2, 3 and 7, and designate them 10. Each of the said devices is axially threaded at both ends and mounted upon threaded rods 11, fixedly connected with brackets 12 attachable by thumb nuts 13 at their ends with a series of bolt holes 14 spaced at the desired distances apart upon the extension 9, the bent part of the leg splint 7, and the body splint 6.

It will be understood that by means of this adjustment the desired set of the turnbuckles can be made such as to draw the leg splint 7 toward the body splint 6, and the extension 9, or move them apart, in either instance to the desired distance.

The turnbuckle device as an entirety is simply a convenient means for adjusting the distances apart of the body splint and the leg splint in the application of my device to

the patient,—and, obviously, mechanically different devices operative to the same purpose may be used instead of the specific device illustrated and described.

5 In connection with the body splint 6, the bands 5 may be applied at advantageous points for best fixation and desired distances apart by resorting to thumb nuts 15 which pass through any one of a plurality of properly placed bolt holes 16 in said body splint 6, as illustrated in Figures 2, 3, and 4, and said bands may also be of any desired length and adapted to be strapped to the body by adhesive plaster or other preferred means.

10 15 17 designates a bridge, see Figures 1, 2, 3, 9, and 11, a good form of which, viewed in the direction of the length of the leg of the patient, will be understood from Figures 1 and 9. The sides 18 of the bridge, are at 20 the bottom, respectively and conveniently connected with the lower end of the body splint 6 and the extension 9, or on 7, by thumb nuts 19 which are adapted to be passed through the bolt holes 14 as shown in 25 Figure 7.

The overhang of cross piece 17 of the bridge is preferably in two parts as shown in Figure 9, and is conveniently provided with a connecting thumb nut 20, a slot 21 30 and bolt holes 22, by the use of which the bridge can be made wider or narrower to fit the patient.

35 By all of the foregoing devices, or their equivalents, it will be obvious that the bridge can be adjusted in any desired position and fitted to the proportions of the patient.

40 28 designates an arm suitably connected with the bridge, conveniently by a clamp nut 24, and extending a given distance, see Figures 1, 2, 7 and 11, outwardly from the bridge, so as to have connected with it a traction or lifting band, or webbing 25, adapted to encompass the thigh of the patient between the pelvic ring 8 and the bridge 17, wherever placed, and permit of 45 such lifting of one end of the broken bone as will bring it into apposition with the other end.

50 The traction band 25 is made of the desired length, and after having been wrapped and adjusted around the thigh of the patient, its free ends, which, as shown in Figure 11, pass through a clamp 26, which holds them 55 in place with regard to the supporting arm 23,—may be pulled up to effect the desired lifting of the leg.

60 In the application of the leg portion 7 of the splint which is bent to conform to the side outlines of the injured leg, I conveniently effect the union or attachment of the splint by providing it with a series of retaining pins 27, see Figures 3, 5, and 10, 65 which pass through apertures 28, and then imbed the calf and said splint member with

a plaster cast such as is shown in Figures 1 and 2 and designated 4. The pins 27 serve to anchor the said leg portion 7 in the plaster cast.

Of course, other means for effecting the 70 union of the leg splint with the leg, such, for instance, as wrapping with straps of adhesive plaster or bandages, may be resorted to. The "Buck" extension may, if desired, be utilized for additional fixation of the 75 splint member 7 to the leg.

The details of formation, dimensions, connection attachment, of the elements which my splint as an entirety comprises, may, of course, be varied without departing from 80 the principle of my invention which, as already explained, comprehends the union or combination of the body and leg members of the splint which are bendable to conform to the body and leg of the patient and when so bent are retained in position,—with extensible elements which are provided with means to, and in fact by the exercise of traction do, force the retained elements apart, and in so doing serve to secure the apposition of the overlapped ends of the fractured bone.

85 Referring to Figures 12, 13 and 14, which represent a typical embodiment of my splint adapted to be employed in connection with a fracture of a humerus, the elements which I employ are essentially the same as those already described in connection with a fracture of a femur, the distinction being that one plaster cast is applied to the forearm and connected with a body cast extending upwardly over the shoulder of the broken arm,—bandages, if desired, wrapping both 90 casts.

95 In this construction, which is simply illustratively portrayed, an upper moldable splint element 29 is connected with a lower moldable splint element 30, by a turnbuckle 31 connected with said upper and lower splint elements by brackets 32 and 33, respectively connected with said elements, and with the threaded rods.

100 Inasmuch as the construction of this upper arm splint so far as its basic elements are concerned, is the same as that already described in connection with the splint for a fractured femur, it is unnecessary further to enlarge upon it except to say that the plaster cast applied to the forearm is designated 34 and the plaster cast over the shoulder 35, 105 while, in addition, bands 36 connected below with a belt band 38 conveniently retain the plaster cast 35 in position.

110 A sling of the character usual in the support of a broken arm is, for clearness of 115 illustration, not shown.

120 It will now be understood that I have devised a new and useful splint for setting and retaining in place of fractures of the long bones of the limbs, which embodies the fea- 125 130

tures of advantage enumerated as desirable, and that while I have in the present instance, shown and described preferred embodiments of it which in practice have been found to give satisfactory and reliable results, it is to be understood that the invention is susceptible of modification in various particulars without departing from its spirit or scope or sacrificing any of its advantages.

10 Having thus described my invention, what I claim as new and desire to secure by Letters Patent, is:—

15 1. A splint which comprises a bendable member firmly attachable above the fracture, a bendable member firmly attachable below the fracture, connecting elements extending from said members, and an adjustable brace connecting opposing splint parts.

20 2. A splint which comprises a bendable member firmly attachable above the fracture, a bendable member firmly attachable below the fracture, connecting elements extending from said members, an adjustable bridge adapted to span opposite splint elements at any desired position, and provision for lateral traction of a bone.

25 3. A splint which comprises a body member firmly attachable above a fracture, an adjustable pelvic ring, a limb member firmly attachable to the body below said fracture, overlapping connections extending from said members, and lengthwise extension means attachable to said connections whereby the reduction of the fracture is effected by said lengthwise extension means.

35 4. A splint comprising a moldable member firmly attachable above a fracture, a moldable member firmly attachable below the fracture, means for effecting the reduc-

tion of said fracture by the lengthwise adjustment of said members, and a bridge spanning the opposite splint members at any desired point above or below the fracture. 40

5. A splint which comprises a moldable member firmly attachable above the fracture, a moldable member firmly attachable below the fracture, and means for effecting the reduction of said fracture by the lengthwise adjustment of said members. 45

6. A splint which comprises a moldable member firmly attachable above the fracture, a moldable member firmly attachable below the fracture, arms extending from said members overlapping at the site of the fracture, and means for effecting the reduction of the fracture by endwise adjustment of said overlapping slideable arms. 55

7. A splint which comprises a moldable member firmly attachable above the fracture, a moldable member firmly attachable below the fracture, arms extending from said members overlapping at the site of the fracture, means for attaching a turnbuckle or other extension device to effect the reduction of the fracture by endwise adjustment of the overlapping and slideable arms, and means on the said overlapping arms to lock them together to retain the separation should it be desired to remove the turnbuckle or other separating device. 60

In testimony that I claim the foregoing as my invention, I have hereunto signed my name this twenty-fourth day of February, 1921.

HARVEY C. MASLAND.

In the presence of:—

JOHN WIEDERSHEIM,
J. BONSALL TAYLOR.
